United States Patent Office.

DANIEL POTTER, OF PEORIA, ILLINOIS.

Letters Patent No. 104,349, dated June 14, 1870.

IMPROVED HAY-BINDER POLE FOR WAGONS.

The Schedule referred to in these Letters Patent and making part of the same.

To all whom it may concern:

Be it known that I, DANIEL POTTER, of Peoria, in the county of Peoria and State of Illinois, have invented a new and valuable Improvement in Hay-Binders; and I do hereby declare that the following is a full, clear, and exact description of the construction and operation of the same, reference being had to the annexed drawing making a part of this specification, and to the letters and figures of reference marked thereon.

Figure 1 of the drawing is a view of my invention in perspective.

Figure 2 is an enlarged view of my device with the rear end of the hay-rack broken off.

Figure 3 is a detail, showing the windlass enlarged.

My invention relates to means for securing loads of loose hay in position while being transported, and consists in a novel arrangement of devices intended to serve efficiently for the purpose mentioned.

A of the drawing represents the bed of a wagon-box or hay-rack, as the case may be; and

B, a standard or fulcrum attached to the rear cross-bar thereof.

D represents a binding-pole pivoted to the fulcrum B, as shown, and having a hook, c, affixed to its front end.

E is a cord or chain attached at one end to the front end of a side rail of the box or rack, while its opposite end is secured to the crank-shaft G, in the manner shown on fig. 2.

G is a shaft arranged in brackets H upon the front end of a bed-plate, and P is a crank by which said shaft is operated.

N represents a ratchet-wheel attached to one end of shaft G, and S a pawl, operating therewith.

The brackets H are screwed to the bed-plate of the box or rack, by means of the rods or bolts r, and the nuts and screws thereon.

To operate my device, I press the binding-pole downward longitudinally upon the top of the load, and draw the cord or chain over the hook c; I then turn the crank P and thereby wind the cord upon the shaft G, until the load is sufficiently bound. When this is accomplished, the pawl S, working in the teeth of ratchet N, holds the pole in place until it is desirable to release it.

I claim as my invention—

The apparatus herein described for binding loaded hay, consisting of the standard B, pole D, cord or chain E, shaft G, crank P, ratchets N, and pawl S, when constructed and arranged substantially as specified.

In testimony that I claim the above, I have hereunto subscribed my name in the presence of two witnesses.

DANIEL POTTER.
